UNITED STATES PATENT OFFICE

HARRY H. BARBER, OF AURORA, ILLINOIS, ASSIGNOR TO BARBER-GREENE COMPANY,
OF AURORA, ILLINOIS, A CORPORATION OF ILLINOIS

SCREENING MECHANISM

Application filed October 7, 1929. Serial No. 397,911.

This invention relates to screening mechanism for conveyors and the like and concerns itself with a system of vibrating screens which eliminates the fine and coarse particles from the intermediate particles.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is a side elevational view of a part of a conveyor embodying my novel screening mechanism.

Figure 2 is an enlarged sectional view through the vibrating mechanism for the screens.

Figure 3 is a rear end elevational view of the conveyor showing the screening mechanism with the vibrator omitted.

Fig. 4 is an enlarged fragmentary vertical sectional view taken transversely of the upper screen.

Fig. 5 is an enlarged sectional view taken upon the line V—V of Fig. 4.

In the drawings there is shown a part of a conveyor including a part of the frame work and a part of the conveyor boom 1 which elevates the material through the usual buckets to the screens. The elevated material first drops upon an inverted V-shaped screen 2 which intercepts the coarse particles which gravitate down the sides of the screen 2 and into chutes 2a which guide the particles to a belt conveyor 3 which conveys the coarse particles to one side of the machine. The intermediate and fine particles pass through the mesh of the inverted V-shaped screen and descend upon a second screen 4 which is a plain one that slopes downwardly and rearwardly and discharges the intermediate particles through a chute 5 at the end thereof. The fine particles escape through the mesh of the screen 4 and drop upon an inclined chute 6 (Figure 1) which conveys the same to the belt conveyor for discharging the same upon one side of the machine with the coarse particles.

A vibrator 7 is mounted upon the screen 4. This vibrator which is well known consists of a housing in which a shaft 8 is journaled. A cam 9 is keyed upon this shaft and a tappet lever 10 which is pivoted intermediate its ends in said housing is operated by said cam. This lever projects through the housing and operates a spring controlled tappet 11 which is provided with a shoe 12 (Figure 3) upon its lower end for engaging the screen 4. The shoe 12 has a rod 13 connected at one end and the other end of said rod is connected to the apex of the screen 2 as shown in Figure 1, whereby the vibrator is susceptible of operating or vibrating both screens simultaneously. The casing for the upper screen is provided with a pair of lateral abutments or shoulders 14 and coil springs 15 are mounted between these shoulders and the top of the screen.

The sides of the screen 4 consists of channel members 16 with their flanges directed outwardly as shown in Figures 3 and 4. The frame of the screen 2 comprises vertical posts 17 upon one end which are secured to plates 16a upon the channel members 16 as shown more clearly in Fig. 5 and vertical posts 18 upon the other end which are secured to the channels 16, the channels 16 being cut away at this end to clear the screen 2. The tops of the posts 17 and 18 are connected by angle members 23. These posts 17 and 18 support the side plates 19 of the frame. A link 20 is secured to the upper end of the frame of the screen 4. This link is connected at its lower end to a lever 21 that moves over a locking segment 22 whereby the inclination of the screen 4 may be varied. During such adjustments of the screen 4, the screen 2 will be caused to tilt accordingly since it is supported upon the screen frame 4.

With this construction, it will be appreciated that the screens are simultaneously vibrated from the same source of power, and that the coarse and fine materials are separated and carried away by the same conveying belt.

I am aware that many changes may be made and numerous details of construction may be varied through a wide range without departing from the principles of this invention, and

I therefore do not purpose limiting the patent granted hereon otherwise than necessitated by the prior art.

I claim as my invention:

- 5 1. In a loader, a screen, chutes upon the sides of the screen, a belt conveyor beneath said chutes, a second screen beneath said first screen for receiving the fine and intermediate particles from said first screen, a chute beneath said second screen for conveying the fine particles to said belt conveyor, means for conducting the intermediate particles from said second screen and means for vibrating said screens.
- 10 15. 2. In a loader, a lower inclined screen, an upper inverted V-shaped screen resting upon the lower screen, a vibrator upon the lower screen having a vibrating member engaging said lower screen and a connection between said vibrating member and the apex of said V-shaped screen.
- 20 15. 3. The combination with an inclined screen, an inverted V-shaped screen resting upon said inclined screen, a vibrator acting upon said inclined screen and a connection between said vibrator and said V-shaped screen.
- 25 4. In a loader, the combination with a conveyor boom, an inverted V-shaped screen beneath the upper end of said boom for receiving material therefrom, chutes extending from the sides of said screen for receiving the coarse particles, a belt conveyor for receiving the coarse particles, an inclined screen beneath said V-shaped screen for receiving the fine and intermediate particles, and a chute for conducting the fine particles to said belt conveyor.
- 30 35. In testimony whereof I have hereunto subscribed my name at Aurora, Kane County, Illinois.

HARRY H. BARBER.
